UNITED STATES PATENT OFFICE.

JOHN MARTIN SIEBERT AND GEORGE LAWRENCE WARREN, OF JOHANNESBURG,
TRANSVAAL, SOUTH AFRICA.

ROCK DRILL.

Application filed July 24, 1926, Serial No. 124,728, and in the Union of South Africa September 23, 1925.

This invention relates to rock-drills or rock-drilling machines of the hammer piston type.

One object of the invention is to provide such a machine with a means which will operate to centre and steady the drill, bit or steel, when it is placed in position in the chuck, rotation sleeve or tool holder of the machine, and so obviate breakages of the steels or drills that frequently occur due to vibration arising from the fact that the drill or steel is not properly centred and steadied.

Another feature relates in particular to a hammer piston drill provided with means for supplying water to the cutting points of the steels, drills or bits used with such machines, in which the water is conducted by means of a water tube which extends axially through the cylinder and hammer piston to the rear end of the drilling machine, at which point the water supply enters the tube. With this kind of water supply attachment difficulty is experienced in maintaining the water supply tube central or truly axial, with the result that breakages of the tube frequently occur or excessive wear takes place, which results in the entrance of air into the water passage occasioning dispersal of dust into the atmosphere and also leakage of the water into the cylinder and other parts of the machine.

Further objects of the present invention are, to construct the rock-drill, the steel, drill or bit, and the water conveying tube in such a way that the latter will be automatically centred or maintained in a position axially of the drill when it is placed in the chuck, rotation sleeve or holder, and so obviate breakage of the water tube; and to prevent the passage of air into the water tube and/or drill, steel or bit, and the entrance of water into the cylinder of the machine.

The invention will be fully explained in connection with the accompanying sheet of drawings, wherein,

Fig. 1 is a part-sectional elevation of a rock-drilling machine of the hammer piston type, incorporating the invention.

Fig. 2 is a part-sectional elevation, drawn to an enlarged scale, of the rear portion of the steel, drill or bit and the water supplying tube, illustrating the means for making the joint or connection between the said parts.

Fig. 3 is a half-sectional elevation of a hol-

low tapered rubber or resilient piece which 55 forms part of the means for making the joint between the water tube and the drill, steel or bit.

Fig. 4 is a half-sectional elevation of a brass or other metal ring or sleeve which is ar- 60 ranged around the water tube inside the hollow tapered piece.

Fig. 5 is a half-sectional elevation of a loose or floating member which is arranged in the chuck or rotation sleeve of the machine 65 around the tapered inner end of the drill, steel or bit, and serves for centering and steadying the end of said drill, steel or bit, and

Fig. 6 is a half-sectional elevation of a 70 modified form of said loose or floating member.

In Fig. 1 the numeral 1 denotes the rock-drill or rock-drilling machine, 2 being the front head and 3 the chuck or rotation sleeve. 75 4 is the water supply tube which is arranged axially of the machine 1 and into the rear end of which the water is conducted through the connections 5.

6 represents the hollow steel, drill or bit— 80 see also Fig. 2—into the rear end of which the forward end of the water tube 4 projects so as to deliver the water into the hole 7 provided axially through the drill, steel or bit 6. The forward end of the water tube 4 is tapered as indicated at 8, and at the rear of said 85 tapered portion it is provided with an enlargement forming an annular shoulder 9. Around the water tube 4 at the rear of the shoulder 9 is arranged the tapered rubber or other resilient piece or sleeve 10—see also Fig. 3—and within the sleeve 10 is placed the loose brass or other suitable metallic ring, bush or tubular piece 11—see also Fig. 4.

As shown in Figs. 1 and 2, the tapered rubber piece or sleeve 10 takes up a position in the rear end of the bore or axial hole 7 of the drill, steel or bit 6, which is shown counter-bored or enlarged, as indicated at 12, to accommodate said sleeve 10 and the enlarged 90 end 9 of the water tube 4. The bush or tubular piece 11 facilitates the intermittent rotary movement of the drill 6, together with the rubber sleeve 10, around the water tube 4.

The passage of water in a rearward direction and of air in a forward direction between the tube 4 and drill, steel or bit 6 is prevented by the rubber or like sleeve 10, so

that the leakage of air into the hollow drill 6 or water into the cylinder of the machine is obviated.

The extremity of the shank or rear end of 5 the bit or steel 6 is rearwardly tapered, and in placing the same in position it is projected through the chuck bush or liner 13 over the enlargement 9 on the forward end of the water supply tube 4, as shown in Fig. 1. 10 The chuck, rotation sleeve or holder 3 for the drill or steel is provided with a loose or floating piece or member 14. In Figs. 1 and 15 5 the member 14 is shown constructed for use in an existing chuck or rotation sleeve, it being made of two different diameters externally, the cylindrical portion of larger diameter loosely fitting the enlarged forward portion of the bore of the chuck, and the shoulder formed between said portion and the rear 20 smaller cylindrical portion engaging the projections formed by the front ends of the flutes 15 of the rotation sleeve 3. The smaller cylindrical portion of the member 14 projects rearwardly into the fluted portion 25 of the rotation sleeve 3, as shown in Fig. 1.

Through the member 14 a tapered hole 16 is formed which fits the tapered rear extremity of the drill, steel or bit 6, the rear end of the latter projecting through to the requisite extent beyond the rear end of said member 14— 30 as shown in Fig. 1—to receive the impacts of the hammer piston 17.

The bush or liner 13, which is fixed in the rotation sleeve 3, is shaped internally closely 35 to fit the shank of the drill or steel 6, in front of the tapered rear end portion, and transmits the rotary motion from the chuck or rotation sleeve 3 to the drill or steel 6.

The rotation sleeve 3, as shown, is preferably constructed with an external annular 40 groove 18 which communicates by means of transverse holes 19 with the interior of said sleeve, and, through the further holes 20 in the front head, with the atmosphere to allow 45 of the escape of any exhaust air that may leak into the rotation sleeve 3.

When the drill or steel 6 is projected

through the chuck bush 13, the tapered inner end of the drill enters the correspondingly tapered hole through the loose or floating member 14 and is thereby centred or brought into axial alignment with the water tube 4. This member 14 also operates to steady the drill or steel 6 when the machine is in operation, and by minimizing vibration prevents 55 breakage of the drill or steel from that cause.

In Fig. 6 we illustrate a different form of the member 14. In this case it is of cylindrical shape or of uniform external diameter from end to end. It will be adapted to fit 60 a rotation sleeve constructed internally to correspond.

What we claim as our invention and desire to protect by Letters Patent is:—

1. The combination with a rock-drilling machine, including a tool holder, a water supply tube and a hollow bit having a tapered shank, of a loose floating member arranged in and loosely fitting the tool holder and adapted to move longitudinally thereof, and tapered internally to receive the tapered shank of the bit, a resilient sleeve arranged around the water tube and tightly fitting the bore of the bit, and a bush positioned intermediate the resilient sleeve and the water supply tube, as set forth.

2. The combination with a rock-drilling machine, including a tool holder, a water supply tube and a hollow bit having a tapered shank, of a loose floating member arranged in, unconnected with and loosely fitting the tool holder and adapted to move longitudinally thereof, and tapered internally to receive the tapered shank of the bit, which shank projects completely through it, and a resilient sleeve arranged around the water tube, housed completely within the tapered shank and tightly fitting the bore of the bit, as set forth.

In testimony whereof we have signed our names to this specification.

JOHN MARTIN SIEBERT.
GEORGE LAWRENCE WARREN.
